(57) **CLAIM**

The ornamental design for a gutter guard assembly as shown and described.

DESCRIPTION

FIG. 1 is a top-left perspective view of a gutter guard assembly, showing a first embodiment of our new design; FIG. 2 is an enlarged view of the section of FIG. 1 identified as FIG. 2;

FIG. 3 is a bottom-right perspective view of the gutter guard assembly of FIG. 1;

FIG. 4 is a top plan view of the gutter guard assembly of FIG. 1;

FIG. 5 is a bottom plan view of the gutter guard assembly of FIG. 1;

FIG. 6 is a front elevation view of the gutter guard assembly of FIG. 1;

FIG. 7 is a rear elevation view of the gutter guard assembly of FIG. 1;

FIG. 8 is a left-side elevation view of the gutter guard assembly of FIG. 1, shown enlarged in scale;

FIG. 9 is a right-side elevation view of the gutter guard assembly of FIG. 1, shown enlarged in scale;

FIG. 10 is a top-left perspective view of a gutter guard assembly, showing a second embodiment of our new design; FIG. 11 is an enlarged view of the section of FIG. 10 identified as FIG. 11;

FIG. 12 is a bottom-right perspective view of the gutter guard assembly of FIG. 10;

FIG. 13 is a top plan view of the gutter guard assembly of FIG. 10;

FIG. 14 is a bottom plan view of the gutter guard assembly of FIG. 10;

FIG. 15 is a front elevation view of the gutter guard assembly of FIG. 10;

FIG. 16 is a rear elevation view of the gutter guard assembly of FIG. 10;

FIG. 17 is a left-side elevation view of the gutter guard assembly of FIG. 10, shown enlarged in scale;

(Continued)

FIG. 18 is a right-side elevation view of the gutter guard assembly of FIG. 10, shown enlarged in scale;
 FIG. 19 is a top-left perspective view of a gutter guard assembly, showing a third embodiment of our new design;
 FIG. 20 is an enlarged view of the section of FIG. 19 identified as FIG. 20;
 FIG. 21 is a bottom-right perspective view of the gutter guard assembly of FIG. 19;
 FIG. 22 is a top plan view of the gutter guard assembly of FIG. 19;
 FIG. 23 is a bottom plan view of the gutter guard assembly of FIG. 19;
 FIG. 24 is a front elevation view of the gutter guard assembly of FIG. 19;
 FIG. 25 is a rear elevation view of the gutter guard assembly of FIG. 19;
 FIG. 26 is a left-side elevation view of the gutter guard assembly of FIG. 19, shown enlarged in scale; and,
 FIG. 27 is a right-side elevation view of the gutter guard assembly of FIG. 19, shown enlarged in scale.
 The broken line circles in FIGS. 1, 2, 10, 11, 19, and 20 define the bounds of the enlargements while all other broken lines are directed to portions of the gutter guard assembly. None of the broken lines form part of the claimed design.
